UNITED STATES PATENT OFFICE.

STEFAN ZIELEZINSKI, OF BOSTON, MASSACHUSETTS.

SHIPPING-PACKAGE.

1,348,682.

Specification of Letters Patent. Patented Aug. 3, 1920.

Application filed January 27, 1920. Serial No. 356,033.

To all whom it may concern:

Be it known that I, STEFAN ZIELEZINSKI, a citizen of the United States of America, and a resident of Boston, in the county of 5 Suffolk and Commonwealth of Massachusetts, have invented certain new and useful Improvements in Shipping-Packages, of which the following is a specification.

This invention relates to shipping cases 10 particularly adapted for use in shipping articles to a regular customer and which cases are designed to be used over and over again, the customer after removing the contents thereof, returning the empty cases to the 15 seller to be used for a subsequent shipment.

The main object of the invention is to provide said casing with permanent addresses of the consignor and consignee of such a character that they cannot be lost or 20 tampered with in transit and which may be quickly reversed when said cases reach their destination in either direction thereby placing the cases in condition for immediate shipment to their next destination.

25 The invention consists primarily of a shipping case having a hinged address plate so mounted thereon that it may be reversed as desired and locked in adjusted position.

The invention further consists in an address plate having addresses on both sides 30 and provided midway of its length with alined trunnions mounted in bearings, said plate being freely movable about the axes of said trunnions when the cover of the case 35 is open and the locking plate moved outwardly.

The invention further consists of a slide- 40 able locking plate coacting with said address plate and preventing movement of said address plate about the axes of said trunnions when the slideable plate has been positioned preparatory to the shipment of said case.

The invention further consists in certain 45 novel features of construction and arrangement of parts which will be understood readily by reference to the description of the drawings and to the claims to be hereinafter given.

50 For the purpose of illustrating the invention, one preferred form thereof is illustrated in the drawings, this form having been found to give satisfactory and reliable results although it is to be understood that 55 the various instrumentalities of which the invention consists can be variously arranged

and organized and the invention is not limited to the precise arrangement and organization of these instrumentalities as herein shown and described, except as required by the scope of the appended claims.

Of the drawings:

Figure 1 represents a perspective view of a shipping case embodying the principles of the present invention.

Fig. 2 represents a plan of a portion of the same showing one of the address plates.

Fig. 3 represents a similar view with the sliding lock-plate partially withdrawn.

Fig. 4 represents a similar view with the 70 address plate reversed.

Fig. 5 represents a vertical section on line 5, 5, on Fig. 2.

Fig. 6 represents a vertical section on line 6, 6, on Fig. 2, and

Fig. 7 represents a similar view to Fig. 5 with the sliding lock-plate withdrawn sufficiently to permit the reversal of the address plate.

Similar characters indicate like parts 80 throughout the several figures of the drawings.

In the drawings, 10 is a front wall of a shipping case, the upper edge of which extends above the end walls 11 thereof.

The upper edge of the rear wall 12 also extends above the end walls 11 and this rear wall 12 is provided with hinges 13 for the cover 14.

It is obvious from an inspection of Fig. 1 90 of the drawings that when the cover 14 is closed, its front edge will abut the inner face of the front wall 10.

The cover is provided with a hinged hasp 15 coacting with a staple 16 adapted to receive a padlock.

The cover 14 has set into its upper face, two rectangular frames 17 which are preferably secured thereto by means of screws 18. Preferably these screws 18 are inserted 100 from the inner face of the cover and threaded to the rectangular frames 17 so that when the cover is down and locked these frames 17 cannot be tampered with.

Beneath the opening in each rectangular frame 17 is an opening 19 in the cover itself.

Each frame 17 is provided with opposed guide grooves 20 in which is slidably mounted the projections 21 extending laterally 110 from a locking plate 22.

Pins 23 extend across the outer ends of the

grooves 20 and coat with the projections 21 to limit the sliding movement of the locking plate 22 in either direction.

When the locking plate 22 is in its rear-most position, the front projections 21 will bear against the pins 23 and the front edge of the plate 22 will coincide with the front edge of the cover 14.

This sliding plate 22 has at its outer end, 10 a downwardly extending ear 24 by means of which the operator may move the plate 22 outwardly into the position indicated in Fig. 7 of the drawings when the cover 14 has been opened.

When the cover 14 is closed the plate 22 will be in the position indicated in Fig. 5 of the drawings with the downwardly projecting ear 24 abutting the inner face of the front wall 10 of the case.

Immediately above the sliding plate 22 is an address plate 25 fitting the opening through the frame 10 and provided with alined trunnions 26 midway of the sides of said plate 25.

The trunnions 26 extend into bearings in the frame 10 about the axes of which the address plate 25 may be moved in either direction when the sliding locking plate 22 is drawn out into the position indicated in Fig. 7 of the drawings.

On the cover 14 there are two rectangular frames 17, one in the upper left hand corner and the other in the lower right hand corner.

The address plates are preferably of metal 35 and the one in the right hand lower corner has stenciled on one face thereof, the name and address of the shipper as indicated at 27, while on the opposite face is stenciled the name and address of the customer to 40 which goods are to be consigned as indicated at 28.

In a similar manner the frame 17 in the upper left hand corner is provided with stenciled names and addresses on the opposite faces thereof of the party or parties 45 shipping the contents of the case.

When the case is ready for shipment, the address at the upper left hand corner indicates from whom the contents of the case are shipped while the address in the lower right hand corner is the address of the party to whom the goods are shipped.

When the case with its contents reaches its destination the recipient removes the contents from the box, pulls out the slides 22, reverses the plates 25, returns the slides 22 to their normal positions, closes the cover 14, locks the same and the empty case is ready for return to the dealer.

It is obvious that by means of this construction, when the goods have been packed and the cover closed, it is absolutely impossible to tamper with the addresses of either the consignee or consignor.

When the address plate 25 is in its normal

position its under face rests against the sliding locking plate 22 and is retained in this position with its outer face flush with the outer face of the frame 17.

This shipping case is particularly adapted 70 for use in shipping motion picture films to the various motion picture theaters from the film distributers.

As soon as a new film is received in the packing case at the theater where said film is 75 to be displayed, it is removed from the case and a film previously displayed is inserted into the box, the addresses changed and the case with the old film immediately returned to the film distributers.

It is believed that the operation and its 80 many advantages will be thoroughly understood without further description.

Having thus described my invention, I 85 claim:

1. A shipping case provided with an opening in a wall thereof; an address plate pivotally mounted therein and adapted to be reversed by movement about the axes of the pivots thereof; and means for locking said 90 address plate in adjusted position.

2. A shipping case provided with an opening in a wall thereof; an address plate pivotally mounted therein and adapted to be reversed by movement about the axes of the pivots thereof; and a sliding plate for locking 95 said address plate in adjusted position.

3. A shipping case provided with an opening through the cover thereof; a reversible address plate therein; and a coacting locking plate therefor adapted to be moved only when the cover is lifted to permit the reversal of the address plate.

4. A shipping case provided with an opening through the cover; a metal frame therefor having alined bearings midway of its length; an address plate having trunnions in said bearings; and a plate slidably mounted in said frame in contact with the inner face of said address plate.

5. A shipping case provided with an opening through the cover; a metal frame therefor having alined bearings midway of its length; an address plate having trunnions in said bearings; and a plate slidably mounted in said frame in contact with the inner face of said address plate and with its forward end registering with the forward edge of said cover.

6. A shipping case provided with an opening through the cover; a metal frame therefor having alined bearings midway of its length; an address plate having trunnions in said bearings; and a plate slidably mounted in said frame in contact with the inner face of said address plate and provided with a downwardly extending ear at its forward end.

7. A shipping case provided with a cover the front edge of which, when closed, abuts 130

- the front wall of said case; an open frame set into an opening in said cover and having guide grooves in opposed walls thereof; a reversible address plate mounted in said frame above said grooves; and a sliding plate in said grooves with its outer end provided with a downturned ear abutting the front wall of the case when said cover is closed.
8. A shipping case provided with a cover the front edge of which, when closed, abuts the front wall of said case; an open frame set into an opening in said cover and having guide grooves in opposed walls perpendicular to the front edge of said cover; a reversible address plate pivotally mounted in said frame above said grooves; a slidable plate having at opposite ends thereof projections in said grooves; and pins extending across said grooves and coacting with said projections for limiting the sliding movement of said slidable plate.
9. A shipping case provided with a cover the front edge of which, when closed, abuts the front wall of said case; an open frame set into an opening in said cover and having guide grooves in opposed walls perpendicular to the front edge of said cover; a reversible address plate pivotally mounted in said frame above said grooves; a slidable plate having at opposite ends thereof projections in said grooves; and pins extending across said grooves and coacting with said projections for limiting the sliding movement of said slidable plate.
- Signed by me at 746-7 Old South Bldg., 35 Boston, Mass., this 21st day of January, 1920.

STEFAN ZIELEZINSKI.
